ANKER L. CHRISTENSEN, OF NEW YORK, N. Y.

BACK SPOT FACER

Application filed June 16, 1927. Serial No. 199,153.

This invention relates to cutting tools and more particularly to back spot facing cutters.

An object of the invention is to provide a simple and effective tool for spot facing metal in relatively inaccessible positions.

One of the important features of the invention relates to the provision of interchangeable parts which may readily be assembled in a variety of combinations so that the work may be done to desired dimensions and may be accurately centered with respect to different sized holes. In order to employ the tool in differently sized holes and to work to different dimensions according to the character of the work required, the tool may be readily and easily dismantled and quickly assembled.

Another feature of the invention relates to the provision of relatively cheap and easily replaceable means for positively centering the tool so as to produce work of increased accuracy and precision.

According to another feature of the invention a long powerful drive is secured, and thus a tool having increased life is obtained.

According to another feature a plural key drive is provided, thus giving increased strength and more accurate alinement under working pressure.

According to still another feature a retaining ring holds the cutting tool in position and distributes and equalizes the strains set up during the cutting operation.

Another important feature of the invention is the provision of a back spot facing tool of simple construction which is economical to manufacture and which may be readily formed of conventional raw material readily available in the market.

Other objects will appear from the following description taken in connection with the accompanying drawings in which—

Fig. 1 is a vertical cross-section of a dismantled tool shown in proximity to a mass of metal which is to be operated upon;

Fig. 2 is a view of the assembled tool in operation;

Fig. 3 is a section taken on the line 3—3 of Fig. 1;

Fig. 4 is a vertical cross-section of the cutter; and

Fig. 5 is a section taken on the line 5—5 of Fig. 4.

Like reference characters denote like parts in the several figures of the drawing.

In the following description and claims, parts, characteristic features and functions will be identified by specific means for convenience of expression, but they are intended to be as generic in their application to similar parts or equivalent construction as the art will permit.

Referring to Fig. 1 there is shown a mass of metal 10 to be worked on, having a hub portion 11, which terminates in a flange 12. The flange 12 is apertured as at 13 and it is understood that it is desired to provide a smooth machined surface at 14, which may be intended, for example, to serve as the seat for a nut. It will be seen that in order to spot face the surface 14 it is necessary to operate through the aperture 13, as the surface to be operated on is relatively inaccessible.

For this purpose there is provided a bar 20, having its drive end 21 splined for engagement with a driving clutch of conventional form (not shown). The bar 20 is formed of heat treated alloy steel. The free end of the bar is accurately turned to a round cross-section as at 22, this section being sufficiently elongated to permit operating through holes of considerable depth, as may be found necessary. A pilot holder 23, substantially

cup shaped in form and having a bore conforming to the section 22 of the bar 20 is mounted thereon and is held securely in place by a blind set screw 24, the point of which enters a shallow notch 25 in the bar 20. A pilot 26, having a bore also conforming to the section 22 of the bar 20 and having its outer wall conforming to the sides of the aperture 13 is mounted on the bar 20 so that one end 27 thereof enters the cupped recess of the pilot holder 23. A blind set screw 28 mounted in the periphery of the pilot holder 23 engages the pilot 26 and maintains it in fixed position relative to the pilot holder 23 and the bar 20.

For separably supporting a cutting tool the free end of the bar 20 is provided with a pair of oppositely positioned slots or keyways as at 30, 31. Each of these slots extend longitudinally of the bar 20 for some distance from the end of the bar, and is widened as at 32 so as to communicate with a second but relatively short slot 33 in parallel relation with the slot 30. The slots shown are 10 for a left hand drive tool; for a right hand drive it is necessary to interchange the slots 33 and 30.

A cutter 40 (see Fig. 4) formed of high speed tool steel is apertured as at 41 to fit 15 snugly on the free end of the bar 20. One end wall 42 is provided with a plurality of cutting teeth 43 for shearing away metal with which the face 42 may be in contact. The cutting edges may be for left hand drive as shown, 20 or reversed for right hand drive as desired. The outer end of the cutter 40 is chamfered as at 44 to form an inclined shoulder 45, thus forming a seat for a retaining ring as will subsequently be set forth. A pair of oppositely 25 disposed slots 46, 47 is cut in the peripheral wall of the cutter 40 extending longitudinally of the cutter from its chamfered end.

For maintaining the tool in assembled form there is also required a pair of keys as at 50, 30 51, and a ring 52. Ring 52 slips over the tool and keys for the purpose of securing the keys to the tool member. Each key has a length conforming to the longitudinal dimension of the widened portion 32 of the slot in the bar 20, and a width such that it extends into the slot as indicated in Figs. 3 and 5. The ring 52 is formed of a metal slightly softer than the metal of the cutting tool 40 and one edge is beveled to conform to the incline of the shoulder 45 of the cutter 40. The internal dimension of the ring 52 is such it seats snugly on the chamfered end of the cutter 40.

The tool is assembled by selecting a pilot 26 having an outer dimension conforming to 45 the size of the aperture 13 through which it is intended to operate. The dash dot line 60 (Fig. 1) indicates the outline of a larger pilot suitable for a larger aperture than that shown. The pilot is slipped into the pilot holder 23 and fastened by the set screw 28 as has been described. The bar 20 and pilot 26 are now inserted in the aperture 13. The keys 50, 51 are now inserted in the slots 46, 47 of a tool 40, the proper size of tool being selected for the work to be done. The ring 52 is then applied to the cutter, and the assembled cutter is mounted on the end of the bar 20, a double bayonet joint being provided by the protruding keys 50, 51 in connection with the slots in the end of the bar.

In operation the bar 20 is rotated, carrying with it the cutting tool 40 which shears off the surface 14 of the metal. The operation may be continued as long as desired until a 65 desired machined surface is obtained.

It will be seen that in operating the tool a balanced drive is obtained, thus providing more strength and greater accuracy in alinement. The driving surface is of considerable length and thus the slots in the bar can be 76 relatively shallow, thereby avoiding undesirable weakening of the bar. The slots and keys can readily be made as long as desired to 75 secure needed strength. The long contact provided effectively avoids any tendency to burr up the parts or of one part attempting to ride over another part of the device. The parts are easily and quickly dismantled by 80 hand without the aid of wrenches. When the pilot becomes worn it can be inexpensively replaced, thus saving the cost of a complete bar.

Where only one side of aperture is to be operated upon continuously a pressed-on fit of the pilot may be employed instead of the interchangeable pilot holder illustrated in the drawings without departing from the spirit of the invention. Other modifications will suggest themselves to those skilled in the art and it is understood that the scope of the invention is not to be determined by the specific form herein disclosed for the purpose of illustration, reference being had to the appendant claims for that purpose.

What is claimed is:

1. A back spot facing tool device comprising a bar having a plurality of keyways, means positioned on said bar for accurately centering said bar with respect to work to be cut, a spot facing cutter, and means for securing said cutter on the end of said bar comprising a plurality of keys for engaging said keyways to secure a balanced drive, and a ring positioned over said cutter and said keys for maintaining said keys in position and for distributing torsion strains about said device.

2. A back spot facing device comprising a bar having a plurality of elongated shallow keyways, means positioned on said bar for accurately centering said bar with respect to work to be cut, a spot facing cutter, and means for securing said tool on the end of said bar comprising a plurality of relatively long keys for engaging said keyways to secure a balanced drive, and a ring positioned over said cutter and said keys for maintaining said keys in position and for distributing torsion strains about said device.

3. The combination with a holder member having a pilot sleeve detachably mounted thereon, of a tool member detachably mounted upon said holder member and adapted to be driven thereby, said holder member having a plurality of slots cut in the end thereof, a plurality of keys for engaging said slots respectively, and means comprising a ring positioned over said tool member and said keys for securing said keys to said tool member.

4. The combination with a holder member

having a pilot sleeve detachably mounted thereon, of a tool member detachably mounted upon said holder member and adapted to be driven thereby, said holder member having 5 a plurality of elongated slots cut in the end thereof, a plurality of elongated keys for engaging said slots respectively, and means comprising a ring positioned over said tool member and said keys and for securing said 10 keys to said tool member.

5. The combination with a holder member having a recessed end to form an inclined shoulder, a pilot sleeve detachably mounted thereon, of a tool member detachably mounted 15 upon said holder member and adapted to be driven thereby, said holder member having a plurality of slots cut in the end thereof, a plurality of keys for engaging said slots respectively, and means comprising an internally bevelled ring positioned over said tool member and said keys and engaging said recessed end for securing said keys to said 20 tool member.

6. The combination with a driving member 25 having a pilot sleeve detachably mounted thereon, of a driven member detachably mounted upon said driving member and adapted to be driven thereby, said driving member having a plurality of slots cut symmetrically in the end thereof, a plurality of 30 keys for engaging said slots respectively, and means comprising a ring positioned over said driven member and said keys for securing said keys to said driven member.

35 7. The combination with a holder member having a pilot sleeve detachably mounted thereon, of a cutting tool detachably mounted upon said holder member and adapted to be driven thereby, said holder member having a plurality of slots cut in the end thereof, a plurality of keys for engaging said slots respectively, and means comprising a ring positioned over said cutting tool and said keys for securing said keys to said cutting tool.

45 8. The combination with a holder member having a pilot sleeve detachably mounted thereon, of a cutting tool detachably mounted upon said holder member and adapted to be driven thereby, said holder member having a plurality of diametrically opposed slots cut 50 in the end thereof, a plurality of keys for engaging said slots respectively, and means comprising a ring positioned over said cutting tool and said keys for securing said keys 55 to said cutting tool.

Signed at Harrison, in the county of Hudson and State of New Jersey, this 15th day of June, A. D. 1927.

ANKER L. CHRISTENSEN.
